UNITED STATES PATENT OFFICE.

JAMES A. LANNING, OF CAMDEN, NEW JERSEY.

DESIGN FOR A JAR.

SPECIFICATION forming part of Design No. 22,751, dated August 29, 1893.

Application filed July 6, 1893. Serial No. 479,755. Term of patent 7 years.

To all whom it may concern:

Be it known that I, JAMES A. LANNING, a citizen of the United States, residing at Camden, in the county of Camden and State of New Jersey, have invented and produced a new and original Design for Canning and Preserving Jars, of which the following is a specification.

The invention consists in a jar composed of 10 a truncated-cone body, provided at its apex end with an enlarged neck.

On reference to the accompanying sheet of drawings making a part of this specification: Figure 1 is a vertical surface-view. Fig. 2 is 15 a vertical and diametrical section, and Fig. 3 is a plan view.

Similar letters refer to similar parts in the several views.

A is a canning and preserving-jar composed of a truncated-cone body B, tapering from its bottom or base C to its apex end D, and an enlarged neck E.

I claim—

The design for a canning and preserving-jar, substantially as herein shown and described.

In testimony whereof I affix my signature in presence of two witnesses.

JAMES A. LANNING.

Witnesses:

FRANCIS D. PASTORIUS,
JAMES M. CASSADY.
